Hardway, Cathy
Attorney

UNITED STATES PATENT OFFICE.

WENZEL J. DVORAK, OF SUNSET HEIGHTS, TEXAS.

BOILER FURNACE.

Application filed April 10, 1923. Serial No. 631,082.

To all whom it may concern:

Be it known that I, WENZEL J. DVORAK, citizen of Czechoslovakia, residing at Sunset Heights, in the county of Harris and 5 State of Texas, have invented certain new and useful Improvements in Boiler Furnaces, of which the following is a specification.

This invention relates to new and useful 10 improvements in a boiler furnace.

One object of the invention is to provide a furnace formed of independent sections with expansion joints between them so that the walls of the furnace will not crack when 15 subjected to varying degrees of temperature.

Another object of the invention is to provide a furnace of the character described having hollow walls which will greatly retard the transmission of heat, thus saving in 20 fuel and reducing the heat in the boiler room.

Another object of the invention is to provide a furnace of the character described 25 whose walls are reinforced and the sections or parts thereof are securely tied together by the reinforcing rods of the different parts, thus forming a very strong structure as well as a structure which can be cheaply 30 erected and readily repaired, and which will not crack owing to variations in heat.

With the above and other objects in view the invention has particular relation to certain novel features of construction, arrangement of parts, and use, an example of which 35 is given in this specification and illustrated in the accompanying drawings, wherein:—

Figure 1 shows a fragmentary side elevation of the furnace.

Figure 2 shows a fragmentary horizontal sectional view and,

Figure 3 shows a fragmentary end elevation.

In the drawings the numeral 1 designates 45 a corner column, and the numeral 2 designates one of the wall columns. These columns are formed of concrete and precast. They have suitable vertical reinforcing rods as 3, 4, said rods being wrapped with reinforcing wires 5, 5. These columns, when set 50 in place, are tied together at the top and bottom by means of suitable tie rods as 6 and 7 which pass through the lower apertures 8 and 9, respectively. These tie rods have 55 the usual head at one end and being thread-

ed at the other end to receive a securing nut. These columns are tied together at their upper ends by means of angle irons as 10 which are bolted thereto, thus forming a suitable framework. The walls of the furnace are 60 formed of sections, each section having a vertical air space as 11, preferably about two inches in width. The outer part of each section as 12 is constructed of a single thickness of common brick and at intervals, 65 through this outer section, there are securing rods as 13 whose ends project into apertures as 14 provided in the columns 1 and 2 to receive them. The inner part 15 of each section is spaced from said outer part 70 forming the space 11 and is of considerable thickness and is built of fire brick. These sections have anchor rods as 16 which have projecting ends which fit into the apertures 17 in the respective columns so as to hold 75 the inner sections 15 in proper position. The aligned inner sections 15 on either side of the wall are spaced from each other and from the intervening column 2, and have opposing vertical channels providing 80 space for a column of fire brick 18, and the end sections are also spaced from the corner column 1, and from the adjacent end of the wall as 19 running at right angles thereto. Between the column 2 and the fire brick column 18 and between the ends of the bricks forming said column 18 and the wall sections there is asbestos as 20, and between the sections 15, 15 and 19, there is preferably 85 a sealing formed of ground fire brick and fire clay 21 which makes a tight joint and yet admits a certain amount of expansion and contraction. The outer section 12 of the wall will not be subjected to any considerable variations in temperature and consequently will not be liable to crack while 90 the inner section, being formed of independent units, will not be liable to crack because the units can expand and contract both lengthwise and vertically independent of each other, and there is sufficient space left between the adjacent parts to permit this expansion and contracting without any rupture to the structure of the furnace.

What I claim is:—

1. A furnace including a framework consisting of upright concrete columns, means for anchoring said columns in fixed position relative to each other, an outer wall formed of sections having tie rods whose ends pro- 105
110

ject beyond the sections, apertures in the columns provided to receive said projecting ends, an inner wall spaced from the outer wall and formed of sections between said framework columns, said sections having anchor rods embedded therein which project therefrom, and the framework columns having apertures which receive said projecting ends of said anchor rods, the adjoining 10 ends of said sections of said inside wall having coinciding channels forming a vertical space, and a column of fire brick in said space.

2. A furnace including a framework consisting of upright concrete columns, means for anchoring said columns in fixed position relative to each other, an outer wall formed of sections having the rods whose ends project beyond the sections, apertures in the 15 columns provided to receive said projecting ends, an inner wall spaced from an outer wall and formed of sections between said framework columns, said sections having anchor rods embedded therein which project therefrom, and the framework columns having apertures which receive said projecting 20 ends of said anchor rods, the adjoining ends of said sections of said inside wall having coinciding channels forming a vertical space, a column of fire brick in said space, sealing 25 material sealing the joints between the sections of the inside walls, and asbestos surrounding said column of fire brick.

3. A furnace including a framework consisting of upright concrete columns, means for anchoring said columns in fixed position 35 relative to each other, an outer wall formed of sections having rods whose ends project beyond the sections, apertures in the columns provided to receive said projecting ends, an inner wall spaced from an outer 40 wall and formed of sections between said framework columns, said sections having anchor rods embedded therein which project therefrom, and the framework columns having apertures which receive said projecting 45 ends of said anchor rods, the adjoining ends of said sections of said inside wall having coinciding channels forming a vertical space, a column of fire brick in said space, sealing 50 material sealing the joints between the sections of the inside walls, and asbestos surrounding said column of fire brick.

sealing material sealing the joints between the sections of the inside walls.

3. A furnace including a framework consisting of upright concrete columns, means for anchoring said columns in fixed position 35 relative to each other, an outer wall formed of sections having rods whose ends project beyond the sections, apertures in the columns provided to receive said projecting ends, an inner wall spaced from an outer 40 wall and formed of sections between said framework columns, said sections having anchor rods embedded therein which project therefrom, and the framework columns having apertures which receive said projecting 45 ends of said anchor rods, the adjoining ends of said sections of said inside wall having coinciding channels forming a vertical space, a column of fire brick in said space, sealing 50 material sealing the joints between the sections of the inside walls, and asbestos surrounding said column of fire brick.

In testimony whereof I have signed my name to this specification in the presence of two subscribing witnesses.

WENZEL J. DVORAK.
